UNITED STATES PATENT OFFICE.

JAMES A. WHEELER, OF OSWEGO, NEW YORK.

PROCESS OF MAKING ARTIFICIAL LUMBER.

SPECIFICATION forming part of Letters Patent No. 663,056, dated December 4, 1900.

Application filed August 21, 1899. Serial No. 727,940. (No specimens.)

To all whom it may concern:

Be it known that I, JAMES A. WHEELER, of Oswego, in the county of Oswego, in the State of New York, have invented new and useful 5 Improvements in the Manufacture of Artificial Lumber, of which the following is a full, clear, and exact description.

The object of this invention is to produce artificially imitations of different kinds of 10 polished lumber, which imitations shall be hard and durable, more fireproof than natural wood, and useful for flooring, wainscoting, ceiling, doors, and numerous other purposes for which polished natural lumber is desired; 15 and to that end the invention consists in the novel process of producing said imitation, as hereinafter described and claimed.

In carrying out my said invention I proceed as follows: I first form the board or plank 20 from a plastic cement, for which I have used with good success the compound described in my Patent No. 539,928, dated May 28, 1895. I do not, however, limit my present invention to this special compound, as other analogous 25 compounds may be employed for the same purpose. Said compound I tinge corresponding to the color of the wood to be imitated. The compound thus prepared I pack in a mold of the shape of the board or plank to be 30 formed. After the board or plank is thus properly molded I remove it from the mold and then perfectly smooth it on the side which is to be finished. I next place it between metal dies and place it with others 35 similarly prepared in a suitable press to compact and dry the material. The die is heated, and the bottom plate thereof, upon which the back of the molded board or plank rests, is 40 perforated for the escape of moisture and steam. After the board or plank has been thus treated I apply to the smoothened face thereof a perfect imitation of the grain of the natural wood. This imitation of the grain I 45 accomplish in the following manner, indicated in the annexed drawings, in which—

Figure 1 is a plan view of the natural board to be imitated; and Figs. 2 and 3 are side and plan views, respectively, of the artificial board with the roller for applying to said 50 board a facsimile of the grain of the natural board.

B represents a board of natural wood of the kind to be imitated. I plane the face of this board, so as to effectually expose the grain and pores in said face. I then spread 55 over this face a coat of thin coloring-matter to fill the said grain and pores. The color of said coat is to correspond to the color of the grain in the natural wood. After the grain and pores have been thus filled I scrape the 60 surplus coloring-matter from the face of the board in such a manner as to effectually clean the board without removing the coloring-matter from the grain and pores. I then run a gelatin-faced roller R or other suitable 65 elastic transferring-roller over the aforesaid face of the board, so as to obtain on the surface of said roller a perfect impression of the aforesaid grain and pores. I then run said roller over the smoothened face of the aforesaid artificially-formed board or plank C, 70 and thereby transfer thereon the impression on the roller. In this manner I produce an artificial board or plank which is in appearance a perfect facsimile of the natural wood. 75

What I claim is—

The process of manufacturing imitations of natural lumber, the same consisting in preparing a plastic cement, tingeing said cement corresponding to the color of the wood to be 80 imitated, molding said cement in the form of a board or plank smoothing the surface thereof and drying and hardening the same, then taking a board of the natural wood, planing the same to expose the grain thereof, spreading 85 over the planed surface a coat of thin coloring-matter to fill the grain and pores, removing the surplus coloring-matter from said surface, then running over said surface an elastic transferring-roller and thereby 90 producing an imprint of the grain on the roller, and then running said roller over the smooth surface of the aforesaid molded board or plank and thereby transferring the aforesaid imprint on the artificial board or plank 95 substantially as set forth.

JAMES A. WHEELER. [L. S.]
